Patented July 18, 1916.

O. H. BRAATEN Inventor

By Watson E. Coleman
Attorney

UNITED STATES PATENT OFFICE.

OLE H. BRAATEN, OF HALLIDAY, NORTH DAKOTA.

GRAIN-SPOUT DOOR.

1,191,148.

Specification of Letters Patent. Patented July 18, 1916.

Application filed March 13, 1916. Serial No. 83,872.

To all whom it may concern:

Be it known that I, OLE H. BRAATEN, a citizen of the United States, residing at Halliday, in the county of Dunn and State 5 of North Dakota, have invented certain new and useful Improvements in Grain-Spout Doors, of which the following is a specification, reference being had to the accompanying drawings.

10 This invention relates to the grain spouts of elevators and like structures, and particularly to means disposed in the length of the spout and adjacent its relatively small delivery end whereby access may be had to 15 the interior of the spout.

In the grain spouts of elevators as ordinarily constructed, there is great trouble with the spout becoming clogged with stones, horseshoes, wooden blocks, hay and 20 straw, and like foreign articles getting within the spout at its lower or discharge end and blocking the spout, these articles not being able to pass through the small end of the spout. It is very difficult to 25 move these articles and the only way it can be done in spouts as at present constructed is to remove the articles through a hole in the bin to which the spout is connected, fishing for these articles having to be done 30 through this hole in the bin downward through the entire length of the spout. This ordinarily takes from thirty minutes' to an hour's time, during which the spout is incapable of use.

35 The general object of my invention is to do away with this inconvenience by providing a door disposed in the spout adjacent its narrow or delivery end, and further to so construct the door that it will not impede the passage of the material passing 40 through the spout and will not be liable to catch and retain any of this material.

A further object of the invention is the provision of a door having an improved 45 form of latching device whereby the door is held in place, this latching device also constituting a handle for the door.

Other objects will appear in the course of the following description.

50 My invention is illustrated in the accompanying drawings, wherein:

Figure 1 is a perspective view of a grain distributing spout provided with my improved door; Fig. 2 is a longitudinal sec- 55 tional view of the spout, the door being also shown in section; Fig. 3 is a transverse sec-

tional view of the spout, the door and the keeper being also shown partly in section; Fig. 4 is a perspective detail view of the combined latch and handle; Fig. 5 is a perspective view of the door, detached.

Referring to these drawings, 10 designates a spout leading from a bin 11. This spout as illustrated is rotatably connected with the bin 11 so that it may be rotated around its 60 axis to discharge into any one of a number of hoppers leading to other chutes or spouts in the manner common in grain elevators. Adjacent its delivery end the spout is provided with an opening, designated 12, which 65 is relatively long and has a width very nearly equal the door of the spout. This opening, however, may be made of any suitable length or width. Disposed upon the exterior of the spout, at the smaller end of 70 the opening, is a keeper plate 13 which is riveted or otherwise attached to the spout and has its body outwardly displaced from the plane of the face of the spout so as to form a pocket extending below the opening 75 12 and beyond the side walls of the opening. Disposed above the upper end of the opening is a strap 14, forming a latch 80 keeper.

The door consists of a plate 15 which is transversely curved to fit the curvature of the spout, and which, if the spout is tapered, is likewise reduced in width at its lower end, the lower extremity of this door being adapted to be inserted in the pocket formed 85 by the strap 14. Adjacent the upper edge of the door there is provided a guide strap 16. Mounted upon the door is the handle 17 which is formed of a strip of resilient metal riveted at its lower end to the door, 90 as at 19, and having its upper end extended through the strap 16 and normally extended beyond the upper edge of the door. This resilient strip is preferably longitudinally slotted at 20 just above the intermediate 95 bowed portion of the spring strip for the passage of a stud 21 which passes through the strap 16. The resilient strip, as before stated, is bowed, this bowed portion extending between the strap 16 and the lower end 100 of the strip.

Normally, and when the door is in place, the lower edge of the door is disposed in a pocket 13 and the upper end of the resilient handle is disposed in the strap 14. When 110 it is desired to remove the door, the spring handle is compressed or contracted, thus

15 withdrawing the latching end of the handle from its engagement with the strap 14 and the door then may be readily lifted out from the pocket. The door may be as readily put in place and when in place will be rigidly held by the latching end of the handle.

It will be seen that with this construction it is always easy to obtain access to the lower end of the spout so as to remove therefrom any foreign articles which have lodged there; no matter how large this may be. Furthermore, it will be seen that the inner face of the spout is entirely smooth as the only projections are the heads of the rivets 20 which hold the straps in place.

While I have illustrated a certain definite construction for this door which I believe to be particularly effective, it will of course be understood that the door may be varied 25 in some respects without departing from the spirit of the invention and that the latching device of the door may be changed. The door is particularly adapted to the grain distributing spout of elevators though not necessarily limited to this use.

Having described my invention, what I claim is:

1. The combination with a grain spout having an opening in its wall, of a pocket 30 formed upon the exterior face of the spout adjacent the lower end of the opening, a door having its lower end adapted to be inserted in said pocket, and means for latching the upper end of the door to the wall of 35 the spout, said means comprising a resiliently projected latching member forming a handle for the door.

2. The combination with a grain spout having an opening in its wall, of a pocket 40 formed upon the exterior face of the spout adjacent the lower end of the opening, a door having its lower end adapted to be inserted in said pocket, and means for latching the upper end of the door to the wall 45 of the spout, said means comprising a keeper mounted upon the spout and a handle formed of a resilient strip bent into a loop, one extremity of the strip being attached to the

door, the other extremity being extended parallel to the face of the door and beyond 50 the edge thereof, and a guide strap onto which the straight end of the strip is projected.

3. The combination with a grain spout having an opening, of a pocket formed at 55 the lower edge of the opening, a keeper attached to the spout above the upper edge of the opening, a handle attached at its lower end to the face of the door and formed to provide an outwardly projecting loop and a 60 straight portion adapted to engage beneath said keeper, and a guide strap through which the straight portion of the handle passes.

4. The combination with a closure, of a combined handle and latch mounted thereon 65 comprising a resilient strip bent to form a loop and a straight portion, one end of the strip being attached to the closure, and a guide strap beneath which said portion of the handle passes.

5. The combination with a closure, of a combined handle and latch mounted thereon comprising a resilient strip bent to form a loop and a straight portion, one end of the strip being attached to the closure, and a 75 guide strap beneath which said straight portion of the handle passes, the straight portion of the handle being slotted and the guide strap having a limiting stop projecting into said slot.

6. The combination with an article having an opening and a closure for said opening, of a combined handle and latch mounted upon the closure and including a resiliently compressible handle portion and a 85 straight latching portion normally projected by the compressible portion beyond the edge of the closure, and a keeper upon said article with which said latch is adapted to engage.

In testimony whereof I hereunto affix my signature in the presence of two witnesses.

OLE H. BRAATEN.

Witnesses:

J. H. DREWELOW,
OSCAR H. BRAATEN.
